[57] CLAIM

The ornamental design for a foldable stool, as shown and described.

DESCRIPTION

FIG. 1 is a perspective view of a foldable stool in its extended position showing our new design;

FIG. 2 is a top plan view thereof on a reduced scale; FIG. 3 is a left end elevational view of the stool of FIG. 2;

FIG. 4 is a side elevational view; and

FIG. 5 is a right end elevational view thereof;

FIG. 6 is a perspective view of the stool shown in its folded condition;

FIG. 7 is a top plan view of the stool of FIG. 6 on a reduced scale;

FIG. 8 is a left end elevational view thereof;

FIG. 9 is a side elevational view; and

FIG. 10 is a bottom plan view thereof.
